CHARLES F. BURGESS, OF MADISON, WISCONSIN, ASSIGNEE TO BURGESS BATTERY COMPANY, OF MADISON, WISCONSIN, A CORPORATION OF WISCONSIN.

DRY CELL.

Application filed September 11, 1923. Serial No. 662,064.

The objects of the present invention will become clear from the following description taken in conjunction with the accompanying drawings wherein—

5 Fig. 1 is a fragmentary section of a dry cell illustrating one embodiment of my invention, and

Fig. 2 is a similar section of a modified form.

10 The dry cells illustrated in the drawings are of the sizes commonly used in flashlights and for wireless telegraphy, but certain features of my invention may be used with advantage in dry cells of the larger sizes now commonly used for telephone and ignition work.

In the embodiment illustrated in Fig. 1, the zinc cathode 1, which also serves as the container for other components of the cell, is of seamless sheet zinc shaped from a flat sheet by punching, drawing and upsetting operations, and consequently is without a longitudinal or circumferential seam. Such seamless or drawn cups have a special advantage when used as an element of the invention herein claimed. Centrally positioned within cup 1 is a carbon rod 2 surmounted by a brass contact cap 3. The carbon rod is for the most part enveloped in a core 4 of depolarizing material, such as manganese 25 dioxide, intimately mixed with carbonaceous material, such as graphite, this core being enveloped in a bibulous envelope of cheese cloth, or other suitable material, held in place by a wrapping of thread 5, or in other 30 suitable manner. Interposed between the wrapped core and the zinc cup is a gelatinized electrolyte 6 compounded and used in accordance with known practice.

35 In accordance with the present invention a circumferential bead 7 is formed in the zinc cup near its top, or open end, as shown in the drawing. Resting on the said bead is the means used for sealing the cup. In the embodiment shown in Fig. 1, the sealing 40 means comprises a washer 8 of fibrous material, such as stiff paper suitably paraffined. This washer rests directly on bead 7 and forms a tight joint therewith, and also makes a snug fit with carbon rod 2. Sealing 45 material 9, such as sealing wax, may be poured in above the insulating washer 8 while in a hot and fluid condition, and then may be allowed to harden and tightly seal off the air space 10 which separates washer 8 from the core 4 and paste 6.

In the embodiment illustrated in Fig. 2 where-in the parts are numbered similarly to Fig. 1, the fibrous washer 8 is relatively thick and stiff, and the upper edge of the zinc can is crimped inward and flattened against the outer face of this washer at 11 to hold the washer securely seated on bead 7. Such a closing of the cup is relatively air-tight, but I consider it better practice to pour over said washer a thin layer 9 of sealing material, such as paraffin, allowing the paraffin to flow inward into contact with the carbon rod 3, and thereby reenforcing the joint around the carbon rod where the washer may have been damaged or deformed through assembly manipulations, as by having been forced over the thin brass cup 3 with which the carbon rod is surmounted.

With the construction shown in Fig. 2, the core 4 of the cell may be somewhat higher while still maintaining an adequate air space 10 for the reception of gases given off by the cell in normal operation. In other words, the capacity of the cell can be increased through use of my invention without increasing the overall dimensions of the cell. There are other practical advantages arising through the use of either embodiment of the present invention as here pointed out more at length.

The bead 7 by forming a ridge of smaller diameter on the inside of the can acts as a support or spacer for the washer, and makes possible the use of smaller washers than usual, as it is not necessary to depend on the frictional engagement of the washer with the inside of the can to hold the washer in place. The bead does not allow the washer to go below a predetermined depth, and consequently, the air space between the top 95 of the gelatinized electrolyte and the washer can be maintained constant. Even if the washer be considerably smaller in diameter than the can it will still make a close joint with the bead, and will prevent the hot fluid sealing material or wax from running down inside the air space above the electrolyte. The bead also facilitates assembly by preventing the washer from twisting around at an angle as is sometimes the case when 100 washers are inserted in cups of usual construction not equipped with beads.

Another advantage of the bead is that it reenforces and strengthens the zinc can at its open end. A cell so reenforced is less 110

liable to be deformed as the result of rough handling during storage and shipment.

When the zinc cups are of seamless construction, as illustrated in the drawing, the 5 bead 7 can be readily rolled therein and is entirely smooth and uniform through the entire circumference. Such is not the case with a seamed cup.

Another advantage is that the crimp or 10 bead provides a channel into which spring contacts may be forced to make contact with the zinc of the cell when the cells are arranged in groups as for wireless work.

With the construction shown in Fig. 2, 15 and in addition to the advantages of a longer core, and the reduction in cost of sealing material, it has the further advantage that it is less affected by heat after the cell is finished.

20 The inside crimp at the top edge of the zinc cup materially stiffens the top of the cup, and the thick, tight and immovable fiber washer will stand much abuse, particularly against downward thrust which 25 might fracture a more brittle sealing means. With dry cells, as ordinarily constructed, it often happens that when a cell is dropped, or when the carbon rod is subjected to a sharp blow, the shock will crack the sealing 30 wax, and the carbon rod may even be pushed

down through the cracked seal with resultant cracking and virtual destruction of the fragile molded core with which it is encircled.

I claim:

1. The combination of a dry-cell electrode cup having a bead near its open end, a carbon rod within said cup, a core encircling said rod, a flat washer resting on said bead and making a tight fit with said carbon rod, 40 said washer being spaced from the top of said core to form an air space in uninterrupted communication with said core into which gases may pass freely from said core, the upper edge of said cup being crimped 45 over the edge of said washer to make an air-tight closure for said cup.

2. The combination of a seamless dry-cell electrode cup having a bead near its open end, an insulating washer resting on said bead, a carbon rod fitting tightly in said washer, a core encircling said rod and spaced from said washer to form an air space in uninterrupted communication with said core 50 into which gases may pass freely from said core, and fusible sealing material above said washer and about said rod making an air-tight closure for said cup.

In testimony whereof I affix my signature.

CHARLES F. BURGESSION.
